UNITED STATES PATENT OFFICE.

ALFRED GEORGE HALL, OF NEW BRUNSWICK, NEW JERSEY.

SHOE-LACE HOLDER.

1,331,914.

Specification of Letters Patent. Patented Feb. 24, 1920.

Application filed April 8, 1919. Serial No. 288,502.

To all whom it may concern:

Be it known that I, ALFRED G. HALL, a citizen of the United States, and a resident of New Brunswick, in the county of Middlesex and State of New Jersey, have invented a new and Improved Shoe-Lace Holder, of which the following is a full, clear, and exact description.

It is a well-known fact that considerable difficulty is experienced with properly holding the bow of a shoelace in position. The bow hangs downward and presents an appearance which is not neat, as well as the detrimental feature that it is liable to come untied at the slightest provocation, and which untying occurs more readily in view of the afore-mentioned hanging down of the bows.

I have designed a shoelace holder, more particularly adapted to engage the bow of the shoelace, which will be very inconspicuous and present a neat appearance.

Further, the shoelace will be retained properly, so that it will be practically impossible for the bow to come untied, thus saving a great deal of trouble to the wearer.

Reference is had to the accompanying drawings which illustrate one practical embodiment of this invention, and in which—

30 Figure 1 is a front elevational view of a shoe with my improved device applied thereto;

Fig. 2 is an enlarged detail view of the backing or anchor plate;

35 Fig. 3 is a sectional view of such plate with the lace-retaining means applied thereto; and

Fig. 4 is a side elevation of such lace-retaining means.

40 In these figures the reference numeral 1 indicates the exterior surface of a shoe, adjacent the upper edges and tongue slot of which is mounted a hook-shaped member 2 having its ends extending rearwardly. The hook-shaped member 2 is secured to the shoe 1 by means of an anchor plate 3 which is provided with prongs 4 adjacent its ends and with a, preferably, squared opening 5 into which the squared end 6 of the hook-

shaped member 2 projects, so that any rotational movement of the hook-shaped member 2 with respect to the plate 3 is prevented, any movement between the plate 3 and the shoe surface 1 being eliminated by reason of the prongs 4. The hook-shaped member 55 2 is provided with an enlarged end or head portion 7 for the purpose hereinafter more fully specified.

It will now be noted that the plate 3 is applied to the shoe 1, as indicated in Fig. 1, 60 the hook members 2 having their enlarged heads 7 projecting rearwardly. The shoelace now has its loops made in the conventional manner, but upon tightening the same by pulling the ends of the laces, the wearer 65 passes the loops between the hook-shaped portion and the surface 1 of the shoe, so that upon tightening the shoelace rests in the notchlike portion of the hook 2 formed by virtue of the enlarged head 7. It will now 70 be seen that the lace is held neatly and any possibility of accidental untying of same is effectually prevented.

Having thus described my invention, I claim as new and desire to secure by Letters 75 Patent:

1. A shoelace holder including, in combination with a shoe, a plate secured to the inner face of such shoe, and a hook having its stem secured to such plate, its body projecting through the shoe.

2. A shoelace holder including, in combination with a shoe, a plate secured to the inner face of such shoe, and a hook having its stem projecting through such shoe, said 85 plate being provided with a squared central opening, the stem of the hook being squared and adapted to seat within said opening.

3. A shoelace holder including, in combination with a shoe, a plate secured to the 90 inner face of such shoe, hooks extending through such shoe and being each secured to a plate, and prongs integral with such plate and being adapted to project outwardly through the side walls of the shoe, 95 whereby to retain the parts in applied position.

ALFRED GEORGE HALL.
